Attorney

UNITED STATES PATENT OFFICE.

FREDERICK N. ROSS, OF DETROIT, MICHIGAN, ASSIGNOR TO BUTTON ATTACHING MACHINE COMPANY, OF DETROIT, MICHIGAN, A CORPORATION OF MICHIGAN.

BUTTON.

Application filed September 11, 1922. Serial No. 587,809.

To all whom it may concern:

Be it known that I, FREDERICK N. Ross, citizen of the United States, residing at Detroit, in the county of Wayne and State of Michigan, have invented certain new and useful Improvements in Buttons, of which the following is a specification.

This invention relates to buttons and has for its object an improved button of the type 10 that is ordinarily used on over-all and similar garments.

One of the common forms of buttons of this character is the so-called tack button; that is a button which is formed by a pair of 15 members that are secured to opposite sides of the fabric. One of the buttons is provided with an anvil and the other with a tack point. The tack point is driven through the fabric and turned over on the 20 anvil in the other button part. This locks the two button parts together and to the fabric. However, these parts very easily tear out as ordinarily the fabric is only held by the tack shank.

25 Another very common button used, which is somewhat an improvement on this is the staple type. This simply has two prongs instead of one; these are clenched under a bar carried by the anvil button part.

30 The type of button that I have designed is an improvement on buttons of this character; it not only has a plurality of prongs, but these prongs cooperate with the peculiar shape of both the anvil member and the 35 prong carrying member so that the fabric is pinched around a complete ring thereby taking the strain off the prongs and making it practically impossible to tear the fabric from the button by enlarging the holes through 40 which the prongs protrude. Furthermore, the prongs of the button are so designed in connection with the anvil, that the prongs all turn in one direction and twist about their own axes in encountering the anvil. This 45 securely locks them to the anvil member and allows the prong part to be drawn clear down and clinched upon the fabric.

In the drawings:

Figure 1 is a cross section of the button 50 attached to the fabric taken on the line of 1-1 of Fig. 2.

Figure 2 shows the button attached to a fabric.

Figure 3 is an elevation of the prong part 55 of the button.

Figure 4 is a section taken on the line 4-4 of Figure 1.

The prong part of the button is simply a stamping made of a single piece of metal formed into a ring *a* of half circular cross section or what I term beaded, and preferably three prongs *b* protrude axially from the inside of the ring and are bevelled as at *c* on only one side—all the prongs being bevelled on the same side.

The anvil part of the button comprises a shallow cup *d* which has its edges turned over the shell *e*. The main body of this shell is a cylinder having its edge turned over to form the bead *f* and having the other edge turned out into a flaring collar *g* to be engaged by the turned over edges of the shallow cup portion *d*. The flaring position and the cup portion engage over the enlarged base *h* of the anvil. The head of the 70 anvil is convexo-concave; that is, the outside of the head has a concave annular groove, and at the center the head is formed into a convex hump. This convex-concave construction has important functional relations 75 with respect to the turned-in bead of the shell and the prongs on the other part of the button as will presently appear.

The fabric is designated *j*. It will be seen 80 that the turned-in bead of the shell is spaced from the annular groove in the anvil and is also of less width than the groove leaving an opening *k* of substantially circular cross section, forming an annular prong socket. The button parts are automatically clinched together by suitable automatic machinery 85 which need not here be described, as obviously, the parts could be put together by hand.

The anvil member is inserted under the 90 fabric, the prong member above the fabric, the tips of the prongs substantially registering with the opening *k* leading into the annular prong socket afforded by the anvil and the shell. Obviously if the anvil member is held firmly and the prong member is given a sharp blow, the prongs will enter the angular socket, the bevelled point will cause them to bend all in one direction, and will also cause them to curl up in helices 100 such as shown in Fig. 4. Curling up in this fashion, ample room is given the prongs to enter clear in up to their bases. This brings the inside of the beaded ring *a* tightly down on the fabric and on the inside of 110

the bead of the shell. The consequence is that the goods is looked all around on the inside of the two inter-engaging beads and also on the outside of the hump *m* of the 5 anvil. The consequence is that the strain is taken off from the prongs and transferred to the two engaging beads and the hump, consequently, the goods will not tear nearly as easily as if the strain were on one or 10 more prongs and the cloth around the holes through which they protrude in the fabric.

Not only is this a cheap and easy button to manufacture, but the assembled button efficaciously grips the fabric and takes the 15 strain off the prongs, and furthermore, the fabric is exposed in the center of the ring like prong member making a better looking button in many respects.

What I claim is:

- 20 1. In a button, the combination of an anvil part provided with an anvil and an enclosing shell, and a prong part provided with one or more prongs beveled on one side at their free ends, the anvil and the shell so arranged with respect to the prong or prongs when the same are driven against the anvil they are caused to twist upon their own axes in helices into the socket afforded in the anvil member.
- 30 2. In a button, the combination of an anvil part provided with a shell and an anvil and a prong part formed into a ring having one or more prongs, which may be driven into and clinched in the anvil part.
- 35 3. In a button, the combination of an anvil part provided with a shell and anvil forming a prong socket, and a prong part comprising a ring member having a pair of prongs projecting axially from the inside of 40 the ring member and arranged to be driven into the prong socket of the anvil part and clinched therein.
- 45 4. In a button, the combination of an anvil part provided with an anvil and a shell arranged to afford an annular prong socket,

and a prong part comprising a bead like ring having on the inside of the ring axially projecting prongs arranged to be driven into the annular prong socket of the anvil part and clinched therein.

5. In a button, the combination of an anvil part having an anvil provided with a convex-concave head and a shell having a turned-in bead spaced therefrom to form with the concave portion of the anvil head an annular prong socket and a prong part comprising a bead like ring having axially projecting prongs from the inside of the ring which can be driven into the annular prong socket of the anvil part and clinched 55 therein.

6. In a button, the combination of an anvil part comprising an anvil having a head with an angular concave groove and a center hump and provided with a shell having a turned-in bead engaging over the anvil groove but leaving an opening into the groove, and a prong part comprising a ring having projecting from its inside axially directed prongs bevelled on one side, whereby when the prongs are driven through the opening and into the annular prong socket of the anvil they will be caused to twist 70 into helices.

7. In a button, the combination of an anvil part comprising an anvil having a head formed with an annular concave groove and a hump, and a shell having its end turned over into a bead overhanging the said annular groove but of less width than the same to provide an opening into the annular prong socket, and a prong part comprising a bead like ring having projecting from its inside a plurality of axially directed prongs bevelled on one side at their free ends whereby when they are driven against the anvil they are caused to twist into helices in the prong 80 socket of the anvil part.

In testimony whereof I affix my signature.

FREDERICK N. ROSS
